UNITED STATES PATENT OFFICE.

JOSEPH H. POPE, OF HAMILTON, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON HEELS.

1,086,214.

Specification of Letters Patent.

Patented Feb. 3, 1914.

Application filed December 14, 1909. Serial No. 533,002.

To all whom it may concern:

Be it known that I, JOSEPH H. POPE, a citizen of the United States, residing at Hamilton, in the county of Essex and State 5 of Massachusetts, have invented certain Improvements in Machines for Operating Upon Heels, of which the following description, in connection with the accompanying drawings, is a specification, like 10 reference characters on the drawings indicating like parts in the several figures.

This invention relates to machines for removing the corner formed at the junction 15 of the breast and heel seat of a heel blank, and also for trimming off the surplus material at the ends of a rand attached to said blank.

Heretofore it has been customary to subject heel blanks, which are composed of a 20 number of lifts secured together by cement, to the action of a heel-compressing machine which through the instrumentality of suitable dies compressed the blanks under great pressure and formed a concavity in 25 the surface which was subsequently to be attached to the heel seat of a shoe. In some instances, also, the dies have been constructed to condense the material of the blank at the corner formed at the junction 30 of the breast and heel seat concavity in order to bevel or round off this part of the blank. The removal of this corner prevented the surface of the sole at the shank from being indented when the heel was forced against 35 the shoe by the heel attaching machine, and thereby avoided the appearance of a defacing mark on the sole when the surplus material was removed from the heel by the subsequent operation of the heel breasting machine. 40 By reason of the fact that the condensed material of the blank at the edge of the heel was sometimes detached by the knife of the heel breasting machine and forced against the sole, thereby producing a 45 mark thereon, it has been proposed to cut off this part of the heel blank by a knife, in lieu of removing it by compression, and some machines have accordingly been designed with this end in view.

50 The present invention contemplates certain improvements on machines of this type, and in connection therewith provides also for removing the surplus material at the ends of the rand which ordinarily project more or less beyond the breast end of the

heel blank, and under the present practice existing in shoe factories are trimmed off in a subsequent operation, usually performed by hand.

An important feature of the present invention accordingly consists in combining means for removing the corner at the junction of the breast and seat of a heel blank, with means for removing the surplus material from the ends of a rand which is attached to said blank. As shown in the embodiment of the invention herein selected for illustration, the stock at this corner of the blank is removed by a knife which is preferably supported for movement about 60 a suitably located center, the surplus material is removed from the ends of the rand by a knife which is similarly supported for movement, and suitable means is provided for positioning the blank relatively to said 65 knives, whereby, through appropriate connections with the power shaft of the machine, the knives will be caused to move, alternately, toward and from the work to bevel or round off the corner of the 70 blank, and to trim off the ends of the rand. In connection with such arrangement, I also preferably provide suitable means to 75 clamp the blank in position for action thereon by the two knives, in the manner 80 stated, which is automatically actuated in timed relation to the cutting strokes of the knives so as to clamp a blank in position prior to, and release the blank after, 85 said knives act. With such an arrangement, the operator is merely required to feed 90 blanks to the machine and remove them therefrom, and consequently the machine may be run at a high rate of speed and will require only a small amount of attention on 95 the part of the operator.

I accordingly consider it another very important feature of my invention to provide, in connection with mechanism for removing the corner from a heel blank, and for trimming off the ends of a rand, means automatically actuated, for clamping a blank in position therefor prior to the operation of either of said mechanisms, and for releasing the blank subsequently thereto. The 100 clamping means referred to is preferably moved into and out of clamping position through connections with the power shaft of the machine, and, in order to provide for 105 properly timing the movements of the 110

clamping means relatively to the movements of the devices which remove stock from the blank, a variable speed gearing under the control of the operator may be interposed 5 in said connections.

A further feature of the invention consists in the provision of means for adjusting, independently, either of the knives heretofore referred to, in order that the path 10 of movement of the heel edge-trimming knife, or of the rand trimming knife, may be so varied at the will of the operator as to produce a bevel at the junction of the seat and breast of the heel or to trim away 15 the ends of the rand, on any desired inclination. This feature is of especial importance in that it permits the operator to so set the knives that the bevel at the heel-edge may be carried back toward the rear 20 of the heel, or, as a matter of depth, be extended in the direction of the breast line toward the tread surface of the heel, any predetermined distance, and also that the inclination or bevel formed in severing the 25 ends of the rand may extend back an appropriate distance to accord with the bevel being formed at said heel edge. One arrangement for obtaining such adjustments consists in supporting the knives for movements toward and from the work about pivotal axes, as heretofore suggested, and in providing a suitable guideway along which such axes may be moved in a manner to vary the angular relation of the cutting 30 edges of the knives to the work. In addition to this arrangement, the knives may be connected for further pivotal adjustments with the members upon which they are supported on axes which are independent of 35 those about which the knives turn in their movements toward and from the work.

These, and other features of the invention, including important details of construction and combinations of parts, will be hereinafter more particularly described and claimed.

In the drawings:—Figure 1 represents a longitudinal sectional view of a machine embodying the present invention, on the line 50 1—1, Fig. 2. Fig. 2 is a sectional plan view of the machine shown in Fig. 1 without the heel-positioning and clamping devices, certain portions of the top of the frame being broken away to more clearly show the parts 55 thereunder. Fig. 3 is a detail view, showing in plan the heel-positioning devices and the heel clamp. Fig. 4 illustrates another detail.

The main frame 1 of the machine supports in suitable bearings, 12, a rotatable power shaft, 3, which may have thereon the usual loose pulley 5, and fast pulley 7. The shaft 3 is also shown as being formed or provided with crank arms 9, carrying a crank

pin 10 to which is clamped the two-part 65 sleeve-bearing 11 carried by one end of a link 14. The opposite end of this link is pivotally connected, through a stud or pin 16, with two rocker arms 18 at a suitable point intermediate the ends of said arms 70 which latter are pivotally supported at their lower ends, through studs or pins 20, upon two segmental guides 22, having therein curved ways 34, to be hereinafter described. The upper end of each of the arms 18 is 75 joined for pivotal movements to the inner extremities of two links 26, and two links 40, by suitable pivot pins 24, the links 26 and 40 being, as shown in Fig. 2, arranged in pairs with the members thereof disposed 80 a suitable distance apart on opposite sides of the center of the machine frame. Each of the links 26 is shown as being forked at its inner end to receive the inner end of a link 40 where it is joined to the latter and 85 to the end of a rocker arm 18 through a pin 24. The outer ends of links 26 are shown as having inturned, sleeved extensions 27, which are centrally bored to receive a pivot 90 pin 28, through which the links are connected with an arm 30. The lower part of this arm, as shown in Fig. 2, is preferably of a width to extend between and fit snugly against, the opposite inner faces of the segmental guides 22 in such manner as to support the arm against lateral movement but to permit it to slide freely along between these faces, and the lower end of the arm is provided with a transverse bore to receive a pivot bolt 32, which passes therethrough and 100 also through the curved ways 34 in the guides. One or both ends of the bolt 32 are threaded to receive clamping nuts 33, which may have bearing against washers 35, interposed between the nuts and the frame of 105 the machine, whereby, upon turning the nuts in a direction to cause them to travel outwardly on their threads, the bolt will be unclamped from the frame, and may be moved along the slots 34 to adjust the position of 110 the lower end of the arm; and, when so adjusted, the nuts may be turned oppositely to again clamp the bolt to the frame, and thereby hold the arm in the position to which it was moved. To the upper end portion of 115 the arm 30 is connected, through a pivot bolt 36 and clamping nut thereon, a knife carrier 37 to which is suitably secured a knife 38, provided with angular cutting edges, as shown in Fig. 2, or of any other 120 construction which adapts it to bevel or cut off the upper corner of a heel blank at the point where the breast joins the seat. The pivot bolt 36 and clamping nut permit adjustments of the knife 38 to vary the bevel 125 formed in the operation of cutting off the corner from the heel breast, independently of the adjustments which are afforded by the

movements of the bolt 32 in the slots 34, and by combining these two adjustments the depth, as well as the degree of inclination of the cut, may be varied to greater extents 5 than would be possible through the use of either one of these means for controlling the path of movement of the knife.

The outer ends of the links 40 are shown as being provided with inturned sleeves or 10 bosses 41, which are provided with bores to receive suitable pivot studs or pins 44 for connecting these links, respectively, with the upper end portions of two spaced rocker arms 42. The lower ends of these arms may 15 be provided with pivot bolts 51, which, respectively, are received within the slots 34 of the segmental guides, such studs being preferably threaded at their outer end portions to receive clamping nuts 45, between 20 which and the frame may be interposed washers 46. The arms 42 sustain at their upper ends a knife carrier 43, which may be adjustably secured thereto by a pivot bolt 50 and suitable clamping nut thereon, in 25 similar manner to the knife carrier 37, and a knife 48 is fastened to the carrier 43, as shown. The construction of this knife is such as to adapt it to trim off the two end portions of a rand which is attached to a 30 heel blank when the blank is properly positioned relatively to the path of movement of the knife, and to this end the knife is preferably formed with two separated cutting edges, which may be slightly inclined as 35 illustrated in Fig. 2. The adjustments afforded through the pivot bolts 51 and clamping nuts 45, and through the bolt 50 and its clamping nut, enable the knife 48 to be set at the desired inclination for trimming away 40 the surplus material at the ends of a rand on a bevel which will be inclined in proper proportion to the amount of bevel produced by the knife 38 in cutting off the edge of the heel breast, and the adjustments of the two 45 knives may thus be made with reference to each other in accordance with the requirements of the work.

The heel blank is adapted to be supported in appropriate position for the operation of 50 the heel beveling knife and the rand trimming knife upon a rest or support, and is held thereon against the thrust of the knives by means which is actuated automatically to clamp the blank to the rest before the 55 operation of the knives, and to release the blank immediately thereafter. This heel rest preferably comprises two members 122, which are sustained at a suitable inclination upon an appropriately inclined face formed 60 on an upwardly projecting portion 125 of a plate or cover 121, which is preferably hinged by a pin 123 to the forward extremity of a rigid horizontal cover section 120 of the machine frame, (see Fig. 1). The

projection 125 is shown as being formed 65 with a transverse dove-tailed groove 124 to receive the dove-tailed blocks 126 having the stud bolts 128 which, respectively, project through perforations formed in the rest members 122, and the bolts 128 are threaded 70 at their ends to receive clamping nuts 130. By this construction, the members 122 of the heel-rest may be adjusted transversely of the frame in order to be properly spaced apart for supporting a blank of any given 75 size, and may then be securely held in adjusted position. The lower ends of the rest members are shown as provided with openings 131, which are preferably formed with oppositely beveled walls, flaring outwardly, 80 as shown in Fig. 1. In the rear portion of the cover section 121 is formed an elongated, inclined slot 107 to receive and assist in guiding the supporting member 108 for a heel clamp 110. The heel clamp has two 85 slots 112 to receive the two stud bolts 114 which project from the member 108 and are externally threaded and provided with clamping nuts 116 for holding the heel 90 clamp in different positions of adjustment 95 on said member. The clamp is also shown as having an angularly projecting foot 118, which is arranged to engage the top of a heel blank when the clamp is actuated and hold the blank firmly against the heel rest 95 members 122 during the operation of the knives. Two gages 133 are preferably located upon opposite sides of the foot 118 of the clamp, and serve to determine the lateral position of a blank relatively to the 100 knives, and to assist the operator in properly guiding the blank when he places it on the rest 122, and beneath the clamp. These gages are shown as overlying the sides of the clamp so as to coöperate with the slot 107 in guiding the clamp as it moves toward 105 and from the blank, and are provided with slots 135 through which pass stud-bolts 137, which project rigidly from the cover 121, the stud bolts having screw-threads thereon 110 to receive clamping nuts 139. By this construction, the gages may be suitably adjusted the proper distance from each other, according to the width of the blank which is to be presented to the machine, and may 115 be firmly secured in adjusted position. As herein represented, the heel blank 120 clamp is operated by power derived from the shaft 3 through suitable mechanism which permits of adjustment so as to control, variably, the time occupied by the clamp in moving toward and from a heel blank supported on the rest, in order that such movements may be in proper timed relation to the cutting movements of the knives. Referring 125 now to this mechanism, the shaft 3 is shown as being provided with a disk 60, which may be formed with a square aperture or key-

way to fit over a correspondingly shaped portion of the shaft, or in any equivalent manner to the end that the disk may slide freely along the shaft while being constrained to rotate therewith. The shaft 3 is also shown as provided with an enlargement 55 and a rigid collar 53. A spring 57, which surrounds the enlargement and has bearing at one end against the collar and at its other end against the disk 60, acts to yieldingly hold the disk in frictional engagement with the periphery of another friction disk 62. The disk 62 may be fast to one end of a shaft 64 the opposite end of which is reduced and has bearing in the angular extension of an adjustable supporting rod 68, and the reduced end portion of the shaft is threaded and has applied thereto the nuts 66, for securing it to the rod. The rod 68 is shown as passing through a perforation in a boss 69, extending from a rigid part of the frame of the machine, and is preferably externally threaded to receive two clamping nuts 70, 72, which bear, respectively, against the outer wall of the frame and the inner end of the boss, whereby the adjusting rod, and hence the friction disk 62 and its shaft, may be adjusted for positioning said disk different distances from the center of the disk 60, without, however, disturbing the operative engagement between the disks. The shaft 64, in the construction shown, carries a worm gear 73 which may be connected thereto by a key-way and key, or by other suitable means permitting the shaft 64 to slide in the gear during the adjustments of the friction disk 62. The worm gear 73 meshes with a worm pinion 80, which is fast on a shaft 82, rotatably supported in suitable bearings provided therefor in the machine frame, as shown in Fig. 2. The shaft 82 has keyed or otherwise secured thereto, two eccentrics 84, the straps 86 of which carry arms 88 which are shown as being pivotally connected at their lower ends, through a pin 90, to one arm of a lever 92, suitably fulcrumed on a shaft 94, supported from the frame. The other arm 920, of the lever 92, is shown as supporting anti-friction rolls 96, which are confined between a collar 100, fixed to the rod 98, and a spring 102 which surrounds the rod and is held thereon by the nuts 104, having threaded engagement with the end of the rod. The rod 98 is herein represented as being bifurcated at its upper extremity in order to provide spaced arms 104, which are, respectively, pivotally joined by pins 106, or similar means, to suitably spaced lugs projecting from the lower part of the heel blank clamp support 108, as shown in Fig. 1. The described mechanism for actuating the clamp is so constructed and arranged that said clamp will be alternately lowered and raised to hold a heel blank against the rest 122, and to release it, in proper timed rela-

tion to the movements of the knives 38 and 48; and by adjusting the position of the disk 62, whereby it is located at different distances from the center of the disk 60, the time occupied by said mechanism in moving the clamp into and out of clamping relation to the blank may be controlled. In the movement of the arm 920 of the lever 92 downwardly to cause a heel blank to be clamped against the rest, the spring 102 will yield, more or less, according to the thickness of the blank, and thereby provide the necessary amount of lost motion in the clamp-actuating mechanism to compensate for the variations in height presented by heels of different styles and sizes. The yielding action of this spring is also of advantage in that it permits a certain amount of idle movement of the eccentrics 84 and their connections while the clamp remains in clamping position, in order that a blank may be held on the rest long enough to permit both of the knives to fully act thereon.

It will be observed that in the machine herein shown and described the devices for positioning a heel blank and the clamp and its carrier are located above the knives on the hinged cover 121, and that the clamp carrier 108 is guided in its movements toward and from the blank by devices also located on said cover. With this arrangement, if the pins 106 are removed to disconnect the rod 98 from the clamp carrier, the cover may be lifted to permit access to the knives and the mechanism below the cover for inspection or repairs of the several parts.

In the operation of the machine above described, power being first applied through a belt, or the like, from any suitable source to the tight pulley 7 to effect rotation of the shaft 3, the connections from said shaft to the rocker arms 30 and 42 will cause these arms to oscillate, and carry the knives 38 and 48 toward and from the heel blank support; and the connections from the shaft 3 to the clamp 110 will cause the same to be raised and lowered in proper timed relation to the movements of the knives. When the clamp is elevated sufficiently above the rests 122, the operator will place a heel blank H, with a rand R attached thereto, on the rest members 122 in the position shown in Fig. 1, the blank being properly centered and guided to position by the gages 133, and the clamp will descend until the foot 118 thereon engages the blank and clamps it to the support. Following this operation, the knives will be operated, in turn, to cut away the corner at the junction of the breast and seat of the heel, on a suitable bevel, and to trim off the ends of the rand, on a suitable bevel. The clamp will then be raised to enable the operator to remove that particular heel

blank from the machine and to insert in its place another blank which is to be subjected to the same operations.

The bevels produced by the knives 38 and

5 48 in removing the corner from the heel, and in trimming off the ends of the rand, may be varied at the will of the operator to suit various conditions and requirements of the work, by loosening the clamping nuts 33
10 and 45 and moving the bolts 32 and 51 to the desired positions along the slots 34, and then turning the nuts in a direction to again clamp the bolts tightly to the frame. These adjustments of the bolts are permitted by
15 the pivotal connections between the arms 30 and 42 and the outer ends of links 26 and 40, respectively, and by like connections between the inner ends of said links and the arms 18, without disturbing the functions of
20 the mechanism for oscillating the knives from the crank arm 10. A further adjustment of the knives to control the degree of the bevels produced may be effected through the bolts 36 and 50, and their clamping nuts,
25 whereby the angular relations between the cutting edges of the knives and their supporting rocker arms may also be varied.

Having explained the nature of this invention and described one construction embodying the same, I claim as new and desire to secure by Letters Patent of the United States:—

1. In a machine of the class described, the combination with means for removing the 35 corner from a heel blank, of means operating in time relation therewith for removing the surplus material from the ends of a rand attached to said blank.

2. In a machine of the class described, the 40 combination with means for forming a bevel at the junction of the breast and seat of a heel blank, of means operating in time relation therewith for removing the surplus material from the ends of a rand attached 45 to said blank.

3. In a machine of the class described, the combination with a work support, of means 50 for removing the corner from a heel blank sustained on said work support and means for removing the surplus material from a rand attached to said blank.

4. In a machine of the class described, the combination with a work support, of means 55 for forming a bevel at the junction of the breast and seat of a heel blank sustained on said work support and means for removing the surplus material from a rand attached to said blank.

5. In a machine of the class described, the 60 combination with a work support, of a heel blank beveling knife and a rand end trimming knife associated therewith, and means for actuating said knives.

6. In a machine of the class described, the 65 combination with a work support, of a heel

blank beveling knife and a rand trimming knife arranged for movements relatively to said support, and means for actuating said knives.

7. In a machine of the class described, the 70 combination with a work support, of a heel blank beveling knife and a rand trimming knife arranged for movements relatively to said support, and means for alternately actuating said knives.

8. In a machine of the class described, the 75 combination with a work support, of means for forming a bevel at the junction of the breast and seat of a heel blank sustained on said support and means for trimming off at a bevel the surplus material from a rand attached to the blank, said machine including means for varying said bevels.

9. In a machine of the class described, the 80 combination with a work support, of means for forming a bevel at the junction of the breast and seat of a heel blank sustained on said support and for trimming off at a bevel the surplus material from a rand attached to the blank, said machine including means for relatively varying said bevels.

10. In a machine of the class described, the 85 combination with a work support, of a heel blank beveling knife and a rand trimming knife arranged for movements relatively to said support, said heel blank beveling knife having capacity for adjustment to vary the bevel produced thereby.

11. In a machine of the class described, the 90 combination with a work support, of a heel blank beveling knife and a rand trimming knife arranged for movements relatively to said support, said rand trimming knife having capacity for adjustment to vary the bevel produced thereby in removing the surplus material from a rand.

12. In a machine of the class described, the 95 combination with a work support, of a knife for removing the corner from a heel blank, and a knife for trimming off the ends of a rand attached to the blank, means for actuating said knives, and means for determining the inclination of the paths of movement of said knives relatively to the work.

13. In a machine of the class described, the 100 combination with means for sustaining a heel blank, of a rand trimming knife and a heel beveling knife arranged on opposite sides of said means, and mechanism for effecting alternate reciprocating movements 105 of said knives toward and from the work.

14. In a machine of the class described, the combination with means for sustaining a heel blank, of a heel blank beveling knife and a rand trimming knife arranged, respectively, on opposite sides of said means, and actuating mechanism for said knives.

15. In a machine of the class described, the combination with a work support, of reciprocal beveling knives arranged, respec- 110 115 120 125 130

tively, on opposite sides of said work support, and constructed to remove the corner from a heel blank and to trim off the ends of a rand attached to the blank, and pivotal means for sustaining said knives.

16. In a machine of the class described, the combination with a work support, of reciprocatory beveling knives arranged on opposite sides of said work support and pivotal means for sustaining said knives, said means being adjustable to vary the angle of the bevels produced by the knives.

17. In a machine of the class described, the combination of a work support, a heel blank beveling knife, a rand trimming knife, pivots for sustaining said knives for movements toward and from the work support, and a guide-way in which said pivots are arranged for adjustment to vary the angular relation of the paths of movement of the knives to the work.

18. In a machine of the class described, the combination of a work support, heel beveling and rand trimming knives arranged in operative relation thereto, arms for sustaining said knives for movements toward and from said work support, means for reciprocating said arms to cause the knives to trim off the surplus material from the work, and means connecting one of the knives with its arm arranged for adjustment to vary the angle of the bevel produced by said knife.

19. In a machine of the class described, the combination of a work support, reciprocatory heel beveling and rand trimming knives operatively arranged in relation thereto, arms for sustaining said knives for movement toward and from said work support, and means connecting each of said knives with its arm and arranged for adjustment to vary the angle of the bevel produced by the knife.

20. In a machine of the class described, the combination of a work support, beveling knives operatively arranged in relation thereto, arms for sustaining said knives, pivotal supports for said arms arranged for adjustment to vary the angle of the bevels produced by the knives, and means for connecting the knives with said arms and also capable of adjustment to vary the angle of said bevels.

21. In a machine of the class described, the combination of a work support, movably supported arms located on opposite sides thereof and carrying, respectively, a heel blank beveling knife and a rand trimming knife, and means for imparting oscillating movements to said arms to cause the knives to move toward and from the work support.

22. In a machine of the class described, the combination of a work support, movably-supported arms located on opposite sides thereof and carrying knives, links con-

necting said arms, a pivotally sustained arm connected with said links, and mechanism for actuating the last-named arm to cause the knives to move toward and from the work support.

23. In a machine of the class described, the combination of a work support, a guideway, arms arranged on opposite sides of said work support and sustaining knives, pivotal means for supporting said arms arranged for adjustment in said guideway, pivotally-joined links having their outer ends movably connected with said arms, a rocker arm pivotally connected with said links, and means for actuating said rocker arm to effect movements of the knives toward and from the work support.

24. In a machine of the class described, the combination with a work support, of means for removing the corner from a heel blank, means for trimming the surplus material from a rand, and means for holding the blank in position during the operation of said first-named means.

25. In a machine of the class described, the combination with a work support, of means for removing the corner from a heel blank on said support, means for trimming the surplus material from a rand, and an automatically actuated clamp for holding the blank in position during the operation of said means.

26. In a machine of the class described, the combination with a work support, of means for beveling a heel blank on said support, means for trimming a rand, and a clamp and actuating mechanism therefor constructed and arranged to hold a blank on the work support during the operation of said means, and to release it thereafter.

27. In a machine of the class described, the combination of a work support, means for beveling a heel blank, a clamp and actuating mechanism therefor constructed and arranged to hold a blank on the work support during the operation of said means and to release it thereafter, said mechanism including a variable speed device to control the time occupied by said clamp in moving into and out of clamping relation to a blank, and a yielding element between said device and the clamp.

28. In a machine of the class described, the combination of a work support, means for beveling a heel blank, a clamp and actuating mechanism therefor constructed and arranged for holding a blank on the work support during the operation of said means and for releasing it thereafter, and means permitting relative adjustment of operative speed of said beveling means and actuating mechanism whereby a blank may be clamped and released in proper timed relation to the operation of the beveling means.

29. In a machine of the class described,

the combination of a work support, means for beveling a heel blank and for trimming a rand, a clamp and actuating mechanism therefor constructed and arranged for holding a blank on the work support during the operation of said means and for releasing it thereafter, and means permitting relative adjustment of said beveling and trimming means and said actuating mechanism where-
5 by a blank may be clamped and released in proper timed relation to the operation of the beveling and trimming means.

30. In a machine of the class described, the combination of a work support, a heel blank beveling knife and a rand trimming knife and actuating mechanism therefor, a clamp, and, automatic mechanism for causing the clamp to engage and release a blank in proper timed relation to the operation of 15 said knives including a device arranged to yield in order to compensate for blanks of varying thickness.

31. In a machine of the class described, the combination of a beveling knife, a heel blank support comprising spaced members arranged to sustain a blank in operative relation to said knife, and means, permitting independent lateral adjustment of said members, for clamping them to the frame of the 25 machine.

32. In a machine of the class described, the combination with means for supporting a blank, of a clamp arranged for movement toward and from the top of the blank, and 35 adjustable gages for determining the lateral position of the blank, said gages being also arranged to guide the clamp.

33. In a machine of the class described, the combination of a frame having a slot 40 therein, a work support carried by said frame, side gages for determining the lateral position of a blank on said work support also carried by said frame, a clamp-supporting member arranged for movement 45 in said slot, and a clamp carried by said member and arranged to slide between said gages and frame in moving toward and from a blank on said work support.

34. In a machine of the class described, 50 the combination of a frame, heel trimming devices movably supported thereby and adapted to operate on a heel blank, a cover pivoted to a fixed part of said frame and arranged over said devices, said cover being adapted to swing entirely away from 55 said devices to afford access thereto, and a blank rest carried by said cover constructed and arranged to sustain a blank in operative relation to said devices.

60 35. In a machine of the class described, the combination of an inclined rest comprising spaced members arranged to sustain a heel blank with an attached rand, a clamp for holding a heel blank on said rest, knives 65 supported for movements on opposite sides

of said rest, and actuating mechanism therefor constructed and arranged to cause the knives to cut a corner from the blank and to trim off the ends of the rand.

36. In a machine of the class described, 70 the combination with a work support arranged to sustain a heel blank with an attached rand in operative relation to trimming knives, of knives supported for movement in inclined paths to remove the surplus material from a heel blank and rand on said support, and actuating means for said knives.

37. In a machine of the class described, 80 the combination with a work-support ar- ranged to sustain a heel blank with an at- tached rand in operative relation to trim- ming knives, of knives located on opposite sides of the work-support and arranged for movement in inclined intersecting paths to 85 remove the surplus material from a heel blank and rand on said support.

38. In a machine of the class described, the combination with means arranged to sustain a heel blank with an attached rand 90 in an inclined position, of trimming knives mounted for movement toward and from said means and arranged to remove the sur- plus material from the heel blank and rand.

39. In a machine of the class described, 95 the combination with a work-support ar- ranged to sustain a heel blank with an at- tached rand in an inclined position, of trim- ming knives located upon opposite sides of 100 said support and mounted for oscillating movements toward and from the work-sup- port to trim off the surplus material from the heel blank and rand.

40. In a machine of the class described, the combination with a work-support ar- ranged to sustain a heel blank with an at- tached rand in an inclined position, of trim- ming knives mounted upon horizontal axes 105 arranged on opposite sides of said support, and actuating mechanism for imparting os- cillating movements to said knives to cause 110 them to move in inclined paths in removing the surplus material from the heel blank and rand.

41. In a machine of the class described, 115 the combination of a work support, means for beveling a heel blank, a clamp and actuating mechanism therefor constructed and arranged to hold a blank on the work sup- port during the operation of said means and to release it thereafter, said mechanism in- 120 cluding a variable speed device to control the time occupied by said clamp in moving into, and out of clamping relation to a blank.

42. A machine of the class described hav- 125 ing in combination, means for supporting a heel blank having thereon an attached rand, a rand knife formed with two separated cutting edges, and supported for movement in a path to trim off the ends of the rand, 130

means for adjusting the degree of inclination of the knife relative to the heel blank support, and actuating means for said knife.

43. A machine of the class described having in combination, a work support arranged to sustain a heel blank with an attached rand in an inclined plane, a rand knife formed with two separated cutting edges and supported for movement in a path which intersects said plane, means for relatively adjusting the knife and work support to vary the

degree of the bevel produced by said cutting edges, and actuating means to cause said knife to trim off the ends of the rand.

In testimony whereof I have signed my ¹⁵ name to this specification in the presence of two subscribing witnesses.

JOSEPH H. POPE.
